UNITED STATES PATENT OFFICE

MATSON C. TERRY, OF PHILADELPHIA, PENNSYLVANIA, ASSIGNOR TO WESTINGHOUSE ELECTRIC & MANUFACTURING COMPANY, A CORPORATION OF PENNSYLVANIA

COMPRESSOR

Application filed June 17, 1926. Serial No. 116,620.

My invention relates to compression mechanisms, particularly to compression mechanisms for use in compression refrigerators of small capacity such as are generally used in households and the like and it has for an object to produce apparatus of the character designated which shall be compact, efficient and adapted for operation at high speeds. It has for a further object to provide a compression mechanism which shall be of the rotary type and which shall be capable of pumping very efficiently against considerable pressure difference. It has for a still further object to provide for a complete sealing of the relatively moving parts against the leakage of gaseous fluids being compressed and further to provide an arrangement of expansible chambers and ports which shall permit the full volumetric capacity of said chambers to be utilized in translating the fluid.

These and other objects, which will be made apparent throughout the further description of my invention, may be attained by the employment of the apparatus hereinabove described and illustrated in the accompanying drawings in which:

Fig. 1 is a view, in sectional elevation, showing an arrangement of one form of my compression mechanism in a domestic refrigerating machine;

Fig. 2 is a view, in sectional elevation, of the compression mechanism shown in Fig. 1;

Figs. 3, 4, 5 and 6 are sectional views, taken along the lines III-III, IV-IV, V-V and VI-VI of Fig. 2 respectively, and;

Fig. 7 is a view, in elevation, of the compression mechanism showing the location of the dowel pins.

It is now customary in constructing domestic refrigerating machines of the compression type to employ compressors of the reciprocating type. Such compressors are driven by electric motors of various capacities ranging from $\frac{1}{8}$ to $\frac{1}{2}$ H. P. or more and operating at speeds of from 1700 to 1750 R. P. M. In most of these installations, the compressor is connected to the motor through some speed changing device such as a belt or a reduction gear whereby the com-

pressor is permitted to operate at a speed much lower than the motor. Such an arrangement, however, is undesirable because the speed reducing means creates objectionable operating noises, the amount of space occupied by the compressor is excessive, the cost of manufacture of the compressor is comparatively high, the noises created by the tapping of the valves forming a part of a reciprocating compressor are unavoidable, the necessity, where a belt is employed, of periodically compensating for stretching, as well as numerous other reasons. Of still more importance, however, is the fact that when a compressor is connected to its driving motor through belts or gears, it cannot be readily housed within a single hermetically sealed chamber. Such an arrangement is advisable because otherwise a stuffing box with its well known disadvantages is required for preventing leakage of the refrigerant fluid where the motor shaft enters the compressor.

In order that a compressor of the reciprocating type might be installed complete with its driving motor in a hermetically sealed casing, resort has been made to an arrangement whereby a compressor of the oscillating cylinder type is employed which is capable of operating at high speeds. It is possible to connect such form of compressor directly to its driving motor without the use of any speed reducing means, however, the rapidly oscillating compressor is a source of objectionable vibration.

It has been heretofore generally appreciated that all of the foregoing difficulties could be readily overcome by employing a compressor of the rotary type which could be directly connected to its driving motor. However, rotary compressors, as heretofore constructed, have not been capable of pumping against the required pressure differences without entailing excessive leakage losses and consequently operating at relatively lower efficiencies than reciprocating pumps of the same capacity. I have, therefore, devised a two-stage rotary type pump, which is so constructed that leakage between the rotating parts, friction losses, and thrusts created by unbalanced pressures have been

reduced to a minimum. Such a form of compressor is extremely compact, can be directly connected to the motor, is relatively inexpensive to manufacture and due to the absence 5 of all inlet and exhaust valves, etc., is comparatively noiseless in operation. I will now refer to the drawings for a complete and thorough description of a compression mechanism arranged in accordance with my 10 invention.

Referring to Fig. 1, I show a refrigerating machine of a type disclosed in my co-pending application, Serial No. 70,118, filed November 19, 1925, entitled Refrigerator, and assigned to the Westinghouse Electric and Manufacturing Company. This form of refrigerator comprises a condensing chamber 10, provided with a plurality of cooling fins 10' and in which is disposed a compression 15 mechanism 11 for compressing the refrigerant vapor. By locating the compression mechanism in the condensing chamber 10, no stuffing box is required, the vapor entering 20 the condensing chamber through the inlet 12 and the condensate leaving the chamber through the outlet 13. An evaporator 30 and the expansion valve 30', shown diagrammatically, are connected to the condensing chamber as shown. In order to effect condensation of the refrigerant vapor in the 25 chamber 10, a motor driven fan 14 is superimposed upon the chamber in order to effect a circulation of air over its outer walls and over the cooling fins. It is obvious from 30 inspection of the drawings, that a compression mechanism consisting of a belt or a gear driven compressor connected to a motor is entirely unsuited for use in a refrigerating machine of the character illustrated. This 35 idea of enclosing the motor and pump in the condensing chamber is disclosed in a co-pending application of Andrew A. Kucher, Serial No. 509,672, filed October 22, 1921, and entitled Refrigerating machine.

40 The compression mechanism consists of a motor 15 directly connected through shafting 16 to a compressor 17. The motor 15 is located within a fluid tight housing 19 provided with an upper bearing surface 20 for 45 supporting the compressor. The motor housing 19 is also provided with an upwardly extending cylindrical portion 21 which forms a receptacle 22 for supplying a lubricating fluid to the working parts of the compressor 50 and the motor.

55 The shafting 16 consists of a compressor shaft 25 and a motor shaft 26, the motor shaft 26 having a hollow bore 27 which communicates through a passage 28 with the inlet 12. The motor housing 19 is provided with an upper bearing 23 and a lower bearing 24 for retaining the motor shaft. The motor shaft is provided with a tapered end portion 29 having a key portion 31 which engages a slot 60 provided in the compressor shaft 25 so as

to form a coupling. Angularly disposed openings 32 are provided in the tapered end portion of the motor shaft, these holes being arranged to communicate with a passage 33 formed in the upper portion of the motor housing and connecting with the inlet of the compressor. A spiral groove 34 is provided in the motor shaft for effecting lubrication of the upper bearing 23 and an oil catcher 35 is provided, the contents of which are drained to the interior of the motor shaft by means of a small opening 36.

70 Referring now to Fig. 2, it will be seen that my compressor is of the rotary, vane, multi-stage type comprising a first, or lower pressure stage 41 and a second, or higher pressure, stage 42. An intermediate stationary member 43 is interposed between the first and second stages. As shown in Fig. 6, the first stage 41 consists of a cylinder 44 provided with a concentrically bored surface 45. Located in the cylinder 44 is an inlet 46 which communicates at its lower end with the passage 33 of the motor housing and at its upper end with suction ports 47 provided in the bore of the cylinder. Discharge ports 48 are also located in the cylinder 44, the latter being spaced adjacent to the suction ports 47. Because of the very effective liquid seal maintained in my compressor, the distance intervening between the suction and discharge ports can be made very small without incurring undue leakage. Both suction and discharge ports are preferably made 80 arcuate in shape. The discharge ports 48 communicate with a passage 51 which extends upwardly into the intermediate member 90 wherein it crosses to the opposite side of said member and again rises upwardly to the second stage of the compressor as shown in Fig. 5.

95 As shown in Fig. 4, the second stage 42 of the compressor, like the first stage, comprises a cylinder 52 provided with a concentrate bore 53. This stage has its inlet port 54 arranged to communicate with the passage 51 while its discharge port 55 communicates with a discharge passage 56 arranged to discharge the refrigerant fluid vertically from the upper portion of the compressor. Like the first stage, the suction and discharge ports are made arcuate in shape and are disposed only sufficient distance apart as is required to maintain the proper seal.

100 As shown in Fig. 2, superimposed upon the high-pressure stage 42, is an end plate 58 through which passes a plurality of bolts 59 for securing the end plate 58, the first and second cylinders 44 and 52 and the intermediate member 43 to the motor housing 19 as well as to each other. In addition, the end plate 58 is axially aligned with respect to the second cylinder 52, the second cylinder 52 is aligned with respect to both the intermediate member 43 and the first stage cylinder 44 and 110

75

120

125

130

the latter is aligned with respect to the motor housing 19 by respective dowel pins 61, 62 and 63, as shown in Fig. 7.

Disposed in the bore of the first and second cylinders 44 and 52 are the respective rotors 65 and 66 which are similar in construction excepting their longitudinal lengths which are so proportioned as to make the volumetric capacity of each stage accord with the pressure prevailing therein. Each rotor is of cylindrical form and is disposed eccentrically within the bore of the cylinder in a direction toward the space intervening between the suction and discharge ports. Each rotor is provided with a plurality of radial passages 67 in which are disposed respective vanes 68 engaging the bore of the cylinders through angularly movable tip pieces 69. The slots are so proportioned as to permit the vanes to easily slide radially inward and outward the full amount as determined by the eccentric disposition of the rotor within the cylinder. One face of each tip piece is shaped so as to conform to the bore of the cylinder while the opposite face is made somewhat semi-cylindrical in form so that it is free to angularly adjust itself in a seat provided in the vane.

The compressor shaft 16 is divided into a first stage section 71 and a second stage section 72, each section being integrally formed with its respective rotor. The two shaft sections are connected by a suitable coupling 73 which may be of the finger type and which permits the rotors of each stage to float independently. The shaft sections are carried in an upper bearing 57 provided in the end plate, an intermediate bearing 60 located in the stationary member 43 and a lower bearing 64 provided in the motor housing 19.

Diametral holes 75 are provided in each rotor for spacer pins 76 which are slidable therein. These spacer pins 76 are made of such length as to hold the vanes 68 radially outward from each other a sufficient distance to prevent dislodgment of the sealing pieces 69. However, they are not of sufficient length to press the vane against the bore of the cylinder during any portion of a revolution. On the other hand, the vanes are retained against the bore of the cylinders by a fluid pressure equal to the pressures prevailing in the respective discharge ports of both stages, which pressures are maintained in the space intervening between the vane 68 and the radial passage 67 by suitable ducts 77 and 78 provided in the surface 20 of the motor housing and in the upper face of the intermediate member 43 respectively. The ducts 77 and 78 connect the discharge passages 51 and 56 with the circular passages 79 and 81, respectively, which in turn connect the inner ends of the radial passages 67 of each rotor to each other and thereby insure that the pressure prevailing behind the vanes is equiv-

alent to that prevailing in the respective discharge ports. This circular passage also serves to transfer the fluid from the back of any inwardly moving vane to the back of the outwardly moving vane.

The spacer pins in both the first and second stages are so arranged as to retain the vanes in longitudinal alignment at all times. As will be seen from inspection of Fig. 2, the pins cooperating with each pair of vanes are spaced equally from the center or the ends of the vanes in order to prevent the vanes becoming angularly displaced. This is accomplished also in the second stage where, because of its reduced length, only one spacer pin is utilized for one pair of blades and two spacer pins for the other pair, the first spacer pin being disposed centrally in the rotor and the remaining two spacer pins being spaced equally from the first pin. As one vane of each pair moves radially outward from the shaft coincident with the inward movement of the other vane, I provide in the rotor of the first stage suitable passages 82 which assist the circular passage 79 to transfer the gas behind the vanes back and forth to opposite sides of the rotor.

The suction ports in both stages are preferably arranged so that they remain in communication successively with the chambers formed by adjacent vanes until such time as the volumetric capacity of these chambers has reached a maximum. In this way, the chambers are completely filled with gas before the compressing process is started.

Lubricating fluid is supplied to the compressor by means of an inverted tube 83 which has its lower end communicating with the receptacle 22 and which is connected at its upper end to the bore of the end plate 58. The section 72 of the compressor shaft is provided with a hollow portion 84 for conveying some of the lubricating fluid to the coupling 73. Longitudinal grooves 85, 86 and 87 are also provided for conveying lubricant to the bearings 57, 60 and 64 respectively. A groove 89, as shown in Fig. 6, is provided in the surface 20 of the motor housing 19 and connects the circular groove 79 to the bearing 64 for conveying lubricant thereto. Secured to the end plate 58 is a baffle 88 which is so arranged that any fluid discharged from the passage 56 is impinged thereon and any entrained liquid is deflected downwardly into the lubricating receptacle 22.

The operation of the above embodiment of my invention is as follows:

Assuming the motor 15 to be rotating in a direction indicated by the arrows in Figs. 4 or 6, the compression mechanism draws refrigerant vapor from the evaporator 30 of the refrigerating apparatus through the inlet 12 of the condensing chamber (Fig. 1). Refrigerant vapor passes through the passage 28 to the bore 27 of the motor shaft and

thence through the openings 32 to the passage 33 after which it enters the suction port 47 of the first stage of the compressor. As my form of rotary compressor is capable of pumping against extraordinary pressure differences, it may be utilized in refrigerating machines employing any of the well-known refrigerants. The machine illustrated is disclosed in a co-pending application of Andrew A. Kucher's, Serial No. 550,445, filed April 7, 1922 and entitled Refrigeration. In this machine, the working fluid generally employed consists of a mixture of ethyl chloride and mineral oil which together form a homogeneous mixture or physical solution in all proportions. The Kucher application discloses the idea of constantly entraining a small amount of this fluid in a liquid state into the refrigerant vapor passing to the compressor. Accordingly, the refrigerant vapor entering the inlet 12 has entrained therein a small quantity of liquid. As this entrained liquid has lubricating qualities as well as refrigerating qualities, it lubricates the lower motor bearing 24 in its passage toward the inlet of the compressor.

The refrigerant vapor enters the first-stage suction ports 47 and is discharged to the discharge ports 48 of the first-stage. The compressed vapor then passes through the passage 51 to the inlet port 54 of the second-stage of the compressor from whence it is discharged to the outlet port 55. The vapor is discharged vertically from the compressor through the discharge passage 56 and is deflected against the baffle 88. I have found that when a refrigerating machine of the type disclosed in this application operates in a room of 70 deg. F. with a box temperature of 45 deg. F. average, a suction pressure of 20 in. mercury, an interstage pressure of approximately atmosphere and a discharge pressure of 15 lbs. gauge are maintained.

It will be noted that in compressing the refrigerant vapor, the vanes 68 move radially in and out in their respective rotors. They are retained against the bore of the cylinders 44 and 52 by the discharge pressure prevailing in the ports 48 and 55 respectively. These pressures are conveyed to the backs of the blades by the ducts 77 and 78 which communicate respectively with the circular passages 79 and 81. These passages are so arranged that the vanes in each stage are retained against the bore of their respective cylinders with a pressure which is always a function of the discharge pressure of their associated stage. In this way, the use of all springs is avoided and the vanes are held against the bore of the cylinder with only sufficient pressure to maintain the proper seal. In addition, the volumetric efficiency is not affected as is ordinarily the case with the existing methods which utilize fluid pressure for this purpose. The circular passages

79 and 81 are also utilized to permit the conveyance of fluid displaced by the inward movement of one vane to be transferred to the rear of some other vane which is moving outward and thus prevent the vanes from being retained against the bore of the cylinders by an excessive pressure. Because of the large volumetric displacement effected by the relatively long vanes of the first-stage, the diametral passages 82 are utilized to assist the circular passage 79 in transferring the fluid.

As stated heretofore, the refrigerant vapor passing through the compressor has entrained therein some liquid working fluid, which working fluid has both refrigerating and lubricating qualities. In passing through the compressor, this entrained liquid assists in maintaining the proper oil film between the tips of the vanes and the bore of the cylinders, between the lateral faces of the revolving rotors and their adjacent stationary members and between the suction and discharge ports of each stage. Some of this entrained liquid, however, reaches the discharge port of the second-stage and passes outwardly from the compressor with the compressed refrigerant vapor. Upon being impinged against the baffle 88, this entrained liquid falls downwardly into the receptacle 22. The refrigerant vapor passes outwardly into the condensing chamber 10 wherein it is condensed because of the stream of cooling air circulated by the fan 14. The condensate thus created leaves the condensing chamber through the outlet 13 and passes to the evaporator 30.

The liquid accumulating in the receptacle 22 surrounds the compressor and absorbs the heat generated in its operation. This heat is sufficient to vaporize off the refrigerant component of the liquid, leaving a body of liquid in the receptacle 22 which is substantially a lubricant. In this way, not only is the heat of the compressor absorbed but incidentally a lubricating fluid is produced by what may be termed a process of distillation. This novel method of producing a lubricating fluid is disclosed in a co-pending application of Andrew A. Kucher's, Serial No. 643,364, filed June 4, 1923, and entitled Refrigerator.

The lubricating fluid accumulating in the receptacle 22 is conveyed by the inverted tube 83 and by the discharge pressure prevailing in the condensing chamber to the upper portion of the end plate 58 from whence a quantity drains downwardly through the hollow portion of the compressor shaft to lubricate the coupling 73. The remaining portion drains downwardly through the oil groove 85 and lubricates the upper bearing 57. This lubricant is then deposited upon the upper transverse face of the second-stage rotor 66 and some of it is thrown outward by cen-

trifugal force and serves to seal the lateral face of the rotor while another portion percolates downwardly through the various working clearances to the lower face of the 5 second-stage rotor. Some of this lubricant passes radially outward while another portion passes downwardly through the groove 86 and serves to lubricate the intermediate bearing 60 after which it is joined by some 10 of the lubricant passing over the coupling 73 and is deposited upon the upper face of the first-stage rotor 65 wherein lubrication and sealing is effected in a manner similar to that which takes place in the second-stage, the 15 lubricant ultimately reaching the oil groove 87 of the lower bearing 64.

The lubricant then drains to the coupling 31 and a portion enters the upper motor bearing 23 from whence it is discharged into 20 the oil catcher 35 and is thus prevented from being deposited upon the windings of the motor 15. The remaining portion of the lubricant enters directly into the suction port 33 and is carried into the compression 25 mechanism. Excess lubricating fluid accumulating in the oil catcher 35 is drained into the bore 27 of the motor shaft through the opening 36 and is carried upwardly into the inlet of the compressor together with the 30 liquid which is already entrained in the refrigerant vapor. Any excess lubricating fluid accumulating in the receptacle 22 overflows into the condensing chamber and commingles with the condensed refrigerant and 35 is conveyed to the evaporator.

It will be apparent from the foregoing description that by developing a multi-stage form of vane compressor, I have produced a very efficient and very capable form of rotary pumping mechanism. By conveying lubricating fluid to the working parts in the manner described, a very effective seal is maintained between all relatively moving parts. As a consequence, the pump can be 40 utilized to work against extraordinary pressure differences, the wear of the moving part is reduced to a minimum, while quiet operation is assured. While I have shown my 45 pump as embodied in a refrigerating machine in which the refrigerant vapor entering the compressor has entrained therein a liquid having lubricating qualities, nevertheless, it is to be understood that my compressor may also be readily employed in machines wherein no such entrainment takes 50 place and wherein sealing and lubrication of the working parts is effected merely by the lubricating fluid passing through the inverted tube.

60 While I have shown my invention in but one form, it will be obvious to those skilled in the art that it is not so limited, but is susceptible of various changes and modifications, without departing from the spirit 65 thereof, and I desire, therefore, that only

such limitations shall be placed thereupon as are imposed by the prior art or as are specifically set forth in the appended claims.

What I claim is:

1. In a compression mechanism for elastic fluids, the combination of first and second-stage cylinders, a rotor having transversely slideable vanes fitting each cylinder, an intermediate member for joining the two cylinders and for conveying compressed fluid 70 from the first stage cylinder to the second stage cylinder, means for flexibly coupling the rotors together, and a shaft for driving the rotors, the shaft including means for supplying fluid to the first stage cylinder. 80

2. In a compression mechanism for elastic fluids, the combination of first and second-stage cylinders, an intermediate member, an end member, a rotor having transversely slideable vanes disposed in each cylinder, means embodied within the cylinders and the intermediate member for conveying compressed fluid from the first-stage cylinder to the second stage cylinder, the member being arranged in adjacent end-to-end relation, 85 means for flexibly connecting the rotors together, a shaft for driving the rotors, said shaft including means for supplying fluid to the first-stage cylinder. 90

3. In a compression mechanism for elastic fluids, the combination of first and second-stage cylinders, a rotor disposed in each cylinder, an intermediate member connecting the cylinders, an end member for one cylinder, a motor for driving the rotors, a housing for the motor, a fluid passageway extending through the housing to the first-stage cylinder and means for securing the first and second-stage cylinders, the intermediate member and the end member to said motor housing. 100 105

4. In a compression mechanism for elastic fluids, the combination of a motor, a housing for the motor, a first-stage cylinder superimposed upon the motor housing, a fluid passageway extending through the motor housing to the first-stage cylinder, an intermediate member superimposed upon the first-stage cylinder, a second-stage cylinder superimposed upon the intermediate member, an 110 end member superimposed upon the second-stage cylinder, and rotors provided in both the first and second-stage cylinders. 115

5. In a compression mechanism for elastic fluids, the combination of a motor, a housing for the motor, first and second-stage cylinders, an intermediate member connecting the cylinders, rotors driven by the motor and disposed in the respective cylinders, one of said rotors having laterally extending journal portions located respectively in the intermediate member and in the motor housing, and bearings for the journal portions embodied in the intermediate member and in the motor housing. 120 125

6. In a compression mechanism for elastic fluids, the combination of a motor, a housing for the motor, first and second-stage cylinders, an intermediate member interposed between the cylinders, an end member for one of the cylinders, rotors driven by the motor and disposed in the respective cylinders, each of said rotors having laterally extending journal portions, one of the rotors having its journal portions located respectively in the end member and in the intermediate member and the other rotor having its journal portions located respectively in the intermediate member and in the motor housing, bearings for the rotor journal portions provided in the end member, the intermediate member and the motor housing, and a flexible coupling located in the intermediate member for connecting the first and second-stage rotors to each other.

7. In a compression mechanism for elastic fluids, the combination of a cylinder, a rotor disposed in the cylinder and having diametrically opposed slots located in its outer portion, a vane slidable radially in each slot and fitting the cylinder, means connecting the inner ends of all of the slots to each other, and gas passages extending diametrically across the rotor and connecting opposite slots, whereby said connecting means and said openings relieve the elastic fluid displaced by the inwardly moving vanes to the slots of the outwardly moving vanes.

8. In a compression mechanism for elastic fluids, the combination of a cylinder having inlet and discharge ports, a rotor disposed in the cylinder and having diametrically opposed recesses provided in its outer portion, vanes slidable radially in the recesses and fitting the cylinder, inflexible slidable spacing members interposed between opposite vanes for preventing abnormal relative movement of said vanes, communicating means for connecting the inner ends of each recess to each other and to the discharge port, and separate communicating means provided between oppositely disposed recesses.

9. In a compression mechanism for elastic fluids, the combination of first and second-stage cylinders, a rotor disposed within and fitting each cylinder, a drive shaft for each rotor, a flexible coupling connecting the drive shafts, and means for conveying lubricating fluid through one of the drive shafts to the coupling.

10. In a compression mechanism for elastic fluids, the combination of first and second-stage cylinders superimposed upon each other, a rotor disposed within and fitting each cylinder, an end member superimposed upon the upper cylinder, means for supplying a lubricating fluid to the end member, and means disposed below the lower cylinder for collecting lubricating fluid drainage.

65 11. In a compression mechanism for elastic

fluids, the combination of first and second-stage cylinders disposed in adjacent end-to-end relation, a rotor disposed within and fitting each cylinder, an end member for one of the cylinders, means for supplying a lubricating fluid to the end member, means for distributing a portion of said lubricating fluid to one cylinder and its rotor and for conveying the lubricant escaping from said cylinder and rotor to the remaining cylinder and rotor, and means for conveying another portion of the lubricant supply directly to the last-mentioned cylinder and rotor.

70 12. In a compression mechanism for elastic fluids, the combination of high and low pressure cylinders arranged in adjacent end-to-end relation, a rotor disposed within and fitting each cylinder, an intermediate member for connecting the cylinders, a coupling located within the intermediate member for connecting the rotors, an end member for one of the cylinders, means for supplying a lubricating fluid to said end member, means for conveying a portion of the lubricating fluid from the end member directly to the coupling and thence to one of the cylinders and rotors, and means for conveying another portion of the lubricant supply from the end member to the remaining cylinder and rotor.

75 13. In a compression mechanism for elastic fluids, the combination of first and second-stage cylinders disposed in adjacent end-to-end relation, a rotor disposed within and fitting each cylinder, bearings provided on opposite sides of each rotor, means for supplying lubricant to the bearings associated with one rotor and for conveying the lubricant discharged from said rotor to the bearings of the remaining rotor, and means for conveying lubricant directly to the bearings of the last-mentioned rotor.

80 14. In a compression mechanism for elastic fluids, the combination of first and second-stage cylinders superimposed upon each other, a rotor disposed within and fitting each cylinder, an intermediate member for connecting the cylinders, an end member for the upper cylinder, a lubricant receptacle surrounding the cylinders, a conduit for conveying lubricant from the receptacle to the end member, and means for conveying lubricant from the end member to both the first and second-stage cylinders.

85 15. In a compression mechanism for elastic fluids, the combination of high and low-pressure compressors of the rotary type, the high-pressure compressor being arranged above the low-pressure compressor, a lubricant supply chamber, means for supplying lubricant from the chamber to the moving parts of the high-pressure compressor and from the latter to the low-pressure compressor, means for draining excess lubricant from the compressors to the suction passage of the low-pressure compressor, and means for discharging

ing elastic fluid from the high-pressure compressor over said chamber in order that lubricant carried by the compressed elastic fluid may be deposited therein.

5 16. In a compression mechanism for elastic fluids, the combination of a motor, a housing for the motor, first and second-stage cylinders, an intermediate member interposed between the cylinders, an end member for 10 one of the cylinders, rotors driven by the motor and disposed in the respective cylinders, each of said rotors having laterally extending journal portions, one of the rotors having its journal portions located respectively in 15 the end member and in the intermediate member and the other rotor having its journal portions located respectively in the intermediate member and in the motor housing, and bearings for the rotor journal portions 20 provided in the end member, the intermediate member and the motor housing.

17. In a compression mechanism for elastic fluid, the combination of a cylinder having inlet and discharge ports, a rotor disposed 25 in the cylinder and having diametrically-opposed recesses provided in its outer portion, vanes slidably radially in the recesses and fitting the cylinder, inflexible spacing members interposed between opposite vanes for preventing abnormal relative movement of said 30 vanes, communicating means for connecting the inner ends of all of the recesses to each other, and separate communicating means provided between oppositely disposed recesses.

35 18. In a compression mechanism for elastic fluids, the combination of first and second-stage cylinders disposed in end-to-end relation, a rotor disposed within and fitting each 40 cylinder, an end member provided for one of the cylinders, means for supplying fluid to the end member for lubricating both the first and second-stage cylinders and their associated rotors, and means for collecting lubricant discharged from the cylinder remotely 45 disposed from the end member.

19. In a compression mechanism for elastic fluids, the combination of first and second-stage cylinders disposed in axial relation, a 50 rotor disposed within and fitting each cylinder, an intermediate member for connecting the cylinders, an end member for one of the cylinders, an encased motor for driving the rotors, a lubricant receptacle surrounding the 55 cylinders and supported on the motor casing, a conduit for conveying lubricant from the receptacle to the end member, and means for conveying lubricant from the end member to both the first and second-stage cylinders.

60 20. In a compression mechanism for elastic fluids, the combination of first and second-stage compressors of the rotary type, a lubricant supply chamber communicating with the discharge of the second-stage compressor, 65 means subject to the discharge pressure of

the second stage compressor for conveying lubricant from the chamber to the working parts of the second-stage compressor and first-stage compressor successively, means for conveying at least a portion of the lubricant 70 discharged from the compression mechanism to the inlet of the first-stage compressor, whereby said lubricant is returned to the chamber, and baffle means associated with the discharge of the second-stage compressor for 75 deflecting into the chamber lubricant conveyed to the first-stage compressor and discharged from the second-stage compressor.

In testimony whereof I have hereunto subscribed my name this 10th day of June, 1926. 80
